HINGE

Paul Wimmenauer, Washington, Ind.

Application September 11, 1937, Serial No. 163,470

1 Claim. (Cl. 16—136)

This invention relates to a hinge, the general object of the invention being to provide the leaves of the hinge with parts having semi-spherical sockets therein, and a spherical member fitting in the sockets for pivotally connecting the parts together so that the movable member can easily move on the other member and without noise.

This invention also consists in certain other features of construction and in the combination and arrangement of the several parts to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an elevation of parts of a door and its frame and showing two of the improved hinges connecting the door with the frame, the upper hinge having parts in section.

Figure 2 is a top plan view of the improved hinge.

As shown in these views the hinge includes the two leaves 1 and 2 which are of the usual or any suitable construction and each leaf has a lateral extending part 3 extending from one side edge which is connected with a substantially frusto-conical member 4. The two members 4 of the hinge have the large ends arranged adjacent each other and each of these ends has a semi-spherical recess 5 therein, the two recesses 35 forming a substantially spherical space in which is located a spherical member or ball 6. The ball is large enough to slightly space the two members 4 apart and as will be seen the ball forms a pivotal connection between the two leaves of the hinge and that the member, such as the door A to which the leaves 2 are connected can readily swing with but little friction and no noise on the frame B to which the leaves 1 are connected. A threaded sleeve 7 is located in a threaded 45 hole in the upper member 4 and this member is adjusted to take up wear of the parts, the mem-

ber being adjusted in any suitable manner though the drawing shows it as being formed with a non-circular bore 8 for receiving any suitable form of tool so that it can be turned. This bore also acts as a passage for the lubricants used to lubricate the parts. As shown in Figure 1, the hinges are so arranged that the upper leaf on the door A has its socket part 4 located above the socket part of the adjacent leaf of the frame, and the lower leaf on the door has its socket part 10 arranged below the adjacent socket part of the adjacent leaf on the frame. This arrangement prevents an upward movement of the door relative to the frame from separating the socket parts, which would cause the door to fall from 15 the frame.

It is thought from the foregoing description that the advantages and novel features of the invention will be readily apparent.

It is to be understood that changes may be 20 made in the construction and in the combination and arrangement of the several parts provided that such changes fall within the scope of the appended claim.

Having described the invention, what is 25 claimed as new is:—

A hinge of the class described comprising a pair of leaves, a laterally extending portion formed on a part of one side edge of each leaf, a substantially frusto-conical member formed on 30 the outer free edge of each laterally extending part, the frusto-conical part of one leaf being oppositely arranged with respect to that on the other leaf to place the enlarged ends of said frusto-conical parts adjacent each other, each 35 enlarged end of the frusto-conical part having a semi-spherical recess therein, a spherical member located in the space formed by the two recesses, one of said frusto-conical parts having a threaded bore passing from the recess through 40 its small end and a threaded sleeve in said bore having a concave recess in its inner end for engaging a portion of the spherical member, said sleeve forming means for taking up wear between the parts. 45
